UNITED STATES PATENT OFFICE.

ROBERT Z. FARMER, OF ROSEBURG, OREGON.

ELECTRIC DRILL.

1,358,303.

Specification of Letters Patent. Patented Nov. 9, 1920.

Application filed January 31, 1920. Serial No. 355,378.

To all whom it may concern:

Be it known that I, ROBERT Z. FARMER, a citizen of the United States, residing at Roseburg, in the county of Douglas and 5 State of Oregon, have invented certain new and useful Improvements in Electric Drills, of which the following is a specification, reference being had to the accompanying drawings.

0 This invention relates to drilling machines, and particularly to motor operated drills.

The general object of my invention is to provide a drill of an improved character 5 which is compact in form and thoroughly effective in use.

And a further object is to provide a construction of this character wherein a motor is used with the drill and forming part 0 thereof, and wherein the drill is subjected to a continuous rotary motion and to the impact of a very rapidly operating hammer disposed in the casing of the drill and driven by the motor.

5 A further object is to provide a drill of this character with improved means whereby water or other liquid may be fed to the drill and discharged therethrough as the drill operates, and in this connection to provide a motor operated pumping means for 0 forcing the water through the drill.

Other objects will appear in the course of the following description.

My invention is illustrated in the accompanying drawings, wherein:

Figure 1 is a side elevation of a drill constructed in accordance with my invention;

Fig. 2 is a longitudinal sectional view of 0 the drill shown in Fig. 1;

Fig. 3 is a section on the line 3-3 of Fig. 2;

Fig. 4 is a section on the line 4-4 of Fig. 2;

5 Fig. 5 is a fragmentary enlarged longitudinal section of the casing 11, the drill 24 and the drill chuck;

Fig. 6 is a section on the line 6-6 of Fig. 5;

0 Fig. 7 is a fragmentary side elevation of the forward end of the drill casing showing the latch;

Fig. 8 is a side view of the tappet and a portion of the hammer;

5 Fig. 9 is a section of the inlet valve to cylinder 41;

Fig. 10 is a sectional view of the inlet valve from cylinder 41 into chamber 34.

Referring to these drawings, it will be seen that the casing of my drill is, generally speaking, cylindrical, though it may be of any suitable form, and this casing is formed in three sections 10, 11 and 12, these sections being flanged and held to each other by longitudinally extending bolts 13 which extend through perforations in the flanges and are provided with springs 14. The rear section 12 constitutes a housing for an electric motor, designated generally 15, and the armature shaft 16 of this motor extends longitudinally in suitable bearings through the casing formed of the sections 10, 11 and 12, in the manner illustrated in Fig. 1, and carries upon it the worm 17 disposed in the rear portion of the section 10. Mounted in 75 suitable bearings within the section 10 and extending through the section 11 is a rotatable sleeve 18 carrying upon it a gear wheel 19 engaged by a gear wheel 20 carried upon the motor shaft or armature shaft 16. Thus, 80 this sleeve 18 is continuously rotated.

The forward end of the casing formed by the section 11 is approximately conoidal in form, the axis of the cone being eccentric to the cylindrical section 10, and the apex of 85 the cone is open and provided with an inwardly projecting wall 21 forming a bearing for the forward end of the sleeve 18. Disposed within the forward portion of the sleeve 18 and rotating therewith is a drill 90 chuck 22 which is tubular for a portion of its length and at its forward end is provided with the tapered nipple 23. Adapted to be disposed within the forward end of the sleeve 18 is the drill 24 which is also tubular 95 so as to receive at its forward end the nipple 23. This drill between its ends is formed with an annular, rounded protuberance 25 which bears against the end of the sleeve 18 and is held in place by a latch bar 26 pivoted at one end, as at 27, upon the end face of the conical portion 11, and at its other end engaging in a keeper 28 attached to the outer face of the section 11. The free extremity of this keeper has an inwardly extending lug 29 to prevent the detachment of the latch bar 26 therefrom. The middle portion of the latch bar is arcuate in form so as to surround the drill and when it is in place rests in front of the protuberant portion 25, thus holding the drill from detachment. When the latch bar is lifted, how-

ever, the drill can be removed from the sleeve.

Disposed rearward of the drill chuck 22 and slidably disposed within the sleeve 18 is a steel bar 30 forming a hammer and co-acting with this bar is a tappet 31 having two arms. This tappet is mounted upon a transverse shaft 32 supported in bearings in the section 10, and the shaft is provided with a worm gear wheel 33 with which the worm 17 engages. It will thus be seen that as the drill is rotated, it will be subjected to very rapidly repeated blows by the tappet.

For the purpose of supplying water to the hollow drill, I form the forward end of the section 10 to provide two chambers 34 and 35 connected by a circular duct 36, as illustrated in Fig. 3. The sleeve 18 is formed with an opening or port 37, and the chuck member 22 is also formed with a port 38 which leads to the longitudinally extending bore of the chuck member. Preferably, the port 38 terminates at its exterior in a relatively long slot 39 so as to permit the chuck 25 to have a slight oscillation without communication between the chamber 35 and the interior of the drill being broken. The chamber 34, as illustrated in Fig. 2, communicates by a port 40 with a pumping chamber 30 or cylinder 41 disposed within the section 10, this chamber in turn communicating by a port 42 with a pipe leading to a source of water or other liquid. Check valves are disposed within the ports 41 and 42. (See 35 Figs. 9 and 10.) Operating within the cylinder is a piston 43 carried by a piston rod which is reciprocated by means of an eccentric 44 mounted on the shaft 16. Upon the inward movement of the piston, water is 40 drawn into the cylinder, and upon the outward movement of the piston, this water is forced into the chamber 34 so that there is a constant pressure of water within the chamber 34, and water will thus be forced under 45 pressure into the hollow bore of the drill.

Preferably the casing of the drill is formed with a base 45 extending laterally and engaging longitudinally extending guides 46, this base being formed with 50 screw-threads engageable by a screw-threaded feed shaft 47 which is provided with any suitable means whereby it may be rotated. By rotating this shaft, it is obvious that the drill as a whole may be forced forward or 55 rearward. It is also obvious that the drill might be mounted so as to do away with the necessity of this shaft for certain kinds of work. It will be noted that each tappet arm has a rounded face on one side and strikes 60 against the end face of the steel hammer 30.

In the operation of this device, the drill will be continuously rotated by means of the gearing heretofore described, and at the same time the drill will receive the impacts 65 of the tappet, the concussion of the drill as

it strikes a stone or other work causing it to spring back again into position to receive another blow of the tappet.

The side rod springs 14 are designed to take the shock off the front head in case the 70 drill is not brought up against the rock to prevent breaking out this front head in case the machine is started with no drill in the drill chuck, the hammer 30 in the latter case forcing the member 22 to strike against the 75 member 26 and thus transmitting the shock to the front head of the machine. Also if drilling is being done and the driller failed to crank the machine up against the bottom of the hole, that is to feed the machine as 80 fast as the drill is cutting, then in that case the hammer 30 would strike square against the member 22 and thus transmit its blow to the drill. The blow would be taken up by the front head of the machine, and the 85 springs 14 would save the hammer from breaking the front head, and it is to be understood that the part 26 not only acts as a clamp holding the drill in place, but as a drill extractor acting to pull out the drill 90 when the machine is retracted after a hole has been drilled.

It will be seen that I have provided a hammer operated chuck drill in which the tappet 31 will strike the hammer 30 very rapidly, 95 and in actual practice will give many more blows upon the drill than is possible with an air drill, while at the same time perfect control is secured of the rotation of the sleeve 18 and the drill itself. This machine is designed to take the place of an ordinary air 100 drill, and thus eliminates the high pressure air tank and water tank with the lengths of hose which feed the drill. This high pressure air tank and the hose are very expensive and very difficult to handle underground. To operate one air drill and supply it with water takes one twenty-five horse power engine and one compressor to furnish 105 130' of air per minute, while with the same amount of horse power it would be possible to operate six of the drills herein described.

It will be obvious that the several sections of the drill may be readily disassembled from each other whenever necessary, and the 110 parts may be readily assembled. By the mechanism which has been described, I secure a drill in which the drill proper is very rapidly and continuously rotated, while at the same time it is rapidly struck by the tappet, and I thus provide a drill which is effective for certain kinds of work and may be used as a mining drill, rock drill and in work of like character.

I claim:

1. A drill of the character described including a rotatably mounted, longitudinally removable drill chuck, motor operated means for continuously rotating the chuck, a hammer disposed behind the chuck, and a 130

motor operated tappet coacting with the hammer.

2. A drill of the character described comprising a casing, a motor operated shaft therein, a drill chuck mounted for rotary movement and for longitudinal movement, means on said shaft for rotating the drill chuck, a transverse shaft carrying a tappet, means for driving one shaft from the other, 10 and a hammer disposed behind the chuck and adapted to be struck by the tappet.

3. A drill construction of the character described including a casing, a motor mounted therein and having a longitudinally extending shaft mounted in bearings in the casing, a sleeve rotatably mounted in the casing, a drill chuck carried by said sleeve and rotatable therein and longitudinally movable, a hammer mounted in the 20 sleeve rearward of the drill chuck and adapted to impact thereon, means for transmitting the motion of the motor shaft to the sleeve to rotate the latter, a transversely extending shaft carrying a tappet coacting 25 with said hammer, and means operatively connecting the motor shaft to the transverse shaft to cause the rotation of the latter.

4. A drill including a hollow drill chuck, 30 adapted to receive a drill, the drill chuck being mounted for rotary and longitudinal movement, a hammer disposed rearward of the drill chuck, motor operated means for rotating the drill chuck, a tappet coacting 35 with the hammer, motor operated means for driving the tappet, and means for feeding water to the drill chuck.

5. A drill including a hollow drill chuck adapted to receive a drill, the drill chuck 40 being mounted for rotary and longitudinal movement, a hammer disposed rearward of the drill chuck, motor operated means for rotating the drill chuck, a tappet coacting with the hammer, motor operated means for 45 driving the tappet, and means for feeding water to the drill chuck, said means including a chamber through which the drill chuck passes, the chuck having a port opening into said chamber, a cylinder having 50 a port opening into the chamber and the port having a check valve, and a piston operatively connected to the shaft to be reciprocated thereby.

6. A drill of the character described comprising a sectional casing having an opening at one end, a sleeve disposed in said opening, a hollow chuck disposed in the sleeve,

the chuck and sleeve being rotatable, the chuck being longitudinally movable, the chuck and sleeve having alining ports leading to the hollow interior of the chuck, the chuck at one end having a nipple adapted to be inserted in the bore of a drill shank, a water chamber mounted in the casing through which the chuck and sleeve pass 60 and into which said ports open, a motor carried in the casing and having a longitudinal shaft, a pumping cylinder having an inlet port and having a port leading into said water chamber, a piston disposed 65 within the cylinder, an eccentric on the shaft operating the piston, a gear wheel on the shaft, a gear wheel on said sleeve meshing therewith whereby the sleeve is rotated, a transverse shaft having a worm gear, a 70 worm on the motor shaft meshing with said worm gear, a hammer disposed within the rear end of the sleeve and reciprocating against the rear end of the chuck, and a tappet mounted upon the transverse shaft and 75 having a plurality of arms engaging the hammer.

7. A drill of the character described including a rotatably mounted drill chuck, motor operated means for continuously operating the chuck, a hammer disposed behind the chuck, and motor operated means for delivering blows upon the hammer.

8. A drill of the character described including a casing, a drill chuck rotatably 90 mounted at one end of the casing, motor operating means for imparting continuous rotation to the chuck, a hammer disposed behind the chuck and motor operating means disposed within the casing for delivering 95 blows upon the hammer.

9. A drill of the character described including a casing, a rotatably mounted drill chuck carried in one end of the casing, a motor disposed within the casing, operative 100 connections between the motor and the drill chuck for continuously rotating the chuck, a hammer mounted for free reciprocation in line with and behind the chuck, means operated by said motor for delivering blows 105 upon the hammer while the chuck is being rotated, and means for feeding water to the chuck, including a pumping device, and means operatively connected to the motor for operating the pumping device.

In testimony whereof I hereunto affix my signature.

ROBERT Z. FARMER.
